SCENIC CROSSOVER TUNNEL FOR TOY
RAILROAD OR SIMILAR ARTICLE

Marshall H. Frisbie, Hamden, Conn.

Application February 12, 1959, Serial No. 54,578

Term of patent 14 years

(Cl. D34—15)

Fig. 1

Fig. 2

Fig. 3

Fig. 4

Fig. 5

Figs. 1 and 2 are perspective views of respectively opposite sides and respectively opposite ends of a scenic crossover tunnel for toy railroad showing my new design.

Fig. 3 is a plan view.

Figs. 4 and 5 are sectional views taken respectively on the planes 4—4 and 5—5 in Fig. 1 looking in the directions of the arrows.

I claim:

The ornamental design for a scenic crossover tunnel for toy railroad or similar article, substantially as shown.
